ABSTRACT OF THE DISCLOSURE

A slide valve is disclosed through which air under pressure is supplied to the burner of a gas stove. The valve is a rectangular opening which is surrounded by a thin rectangular seal assembly formed by two sheet plastic diaphragms providing seals upon the opposite sides of a flat rectangular slide. The diaphragms are rectangular frames around a rectangular opening, and the slide moves transversely of that opening. At one limit of movement of the slide, the opening is completely blocked by the slide. At the other limit of that movement, a number of orifices through the slide are in alignment with the opening through the diaphragms. Hence, the slide may be moved to position a selected number of the orifices in alignment with the opening, thus to regulate the amount of air flow.

This invention is related to that disclosed in the co-pending application of the present inventors and Charles W. Fromm, U.S. Ser. No. 610,980, filed Jan. 23, 1967.

This invention relates to control valves, particularly for supplying air and providing overall control for the burner units of a stove or range of the household or commercial type.

An object of this invention is to provide improved control means for the flow of gas and the like. A further object is to provide improved manual controls for stoves and ranges of the household and commercial types. Another object is to provide flow control means for gases, for example, for supplying air to gas burners. A further object is to provide for the above with structures which are compact, sturdy, easily operated and adjusted, efficient and dependable in use, and adaptable to a wide variety of conditions which are met with in the design and use of such structures. These and other objects will be in part obvious and in part pointed out below.

In the drawings:

FIG. 1 is a perspective view with parts broken away of one embodiment of the invention;

FIGS. 2 and 4 are sectional views respectively on the lines 2—2 and 4—4 of FIG. 1;

FIG. 3 is a sectional view on the line 3—3 of FIG. 2; and,

FIG. 5 is a schematic electrical control circuit.

Referring to FIG. 1 of the drawings, a flat-top stove or cooking range 2 has a base shell construction 4 with a flat top 6 in the form of a plate of heat resistant glass which transmits radiant heat as well as heat by conduction. Positioned directly beneath plate 6 are four infrared radiant burner units 8, 10, 12 and 14, which are identical, and of the construction of unit 12 which is shown in FIG. 4. Stove or range 2 includes a control housing 5 centrally positioned in the front of the base shell construction (see FIG. 2). Control housing 5 encloses a gas and air control assembly 7 including for each of the burner units an air flow control valve 9, a gas cut-off 11, a gas-flow pressure regulator 13 and a gas-mixing venturi 15. Venturi unit 15 maintains a near stoichiometric mixture ratio of the

2

gas and air for infrared radiation operation of its burner unit.

Referring again to FIG. 1, the operation of each of the burner units, 8, 10, 12 and 14 is under the respective control of slides 32, 34, 36 and 38 (see also FIG. 2) mounted at the top of the control housing 5. These slides are identical and each of them may be moved, as represented in FIG. 1, from the fully-closed or off position of slide 38 to the fully-open position of slide 32. Each of these slides controls the supplying of gas and air to its burner unit, and it also energizes the igniter unit. Positioned to the rear of burner unit 14 is a blower 40 which draws in fresh air at 42 and delivers it under pressure through a conduit 44 to an air supply manifold 46 (see also FIG. 2) of the air supply control assembly 48.

Manifold 46 has a side wall 50 and a top wall 52 which is mounted thereon by a row of screws 53. The bottom of the manifold is formed by a valve plate 54 which has four rectangular openings respectively in alignment with slides 32, 34, 36 and 38, and there is a rim 57 which overlies a flange 59 at the bottom of wall 50. Positioned beneath the manifold is a valve plate 61 which is generally coextensive with valve plate 54 and which has slots in which the slides are mounted. Mounted respectively above 25 and below each of the slides and mounted back to back is a pair of identical Teflon diaphragms 64 and 66. Each diaphragm has a central flat sealing portion (68 and 69 respectively), resting against the surface of the slide and a peripheral flange (70 and 71, respectively). Flange 70 is 30 positioned between flange 59 of manifold 46 and valve plate 54, and flange 71 is positioned between valve plate 61 and a coextensive top surface of control housing 5. As shown best in FIGS. 1 and 3, the valve plates and the manifold are clamped to the top of the control housing 5 by five rows of screws 73 which are parallel to the edges of the slides, respectively, between the slides and at the ends of the manifold. Additional screws 75 clamp valve plate 54 to flange 59. Hence, the periphery of each of 35 the diaphragms is clamped by its valve plate and its central portion is somewhat resiliently supported in contact with the surface of its slide.

Each of the diaphragms has a centrally positioned and somewhat rectangular or oblong opening 72 which is closed by the slide when the slide is positioned in the 40 fully-closed position shown. At the left of the center of the slide there is a series of holes or orifices 74 through the slide, which bear sub-numbers 1 to 8. Hence, as the slide is moved to the right from the position shown in FIGS. 2 and 3, hole 74-1 first moves into alignment with 45 or is exposed to openings 72 in its diaphragms 64 and 66, thus to provide an orifice or opening from manifold 46 to manifold 56. Upon further movement additional orifices are exposed to the openings 72 in the two diaphragms, thus 50 providing for the increase of the flow of air into manifold 56, with the maximum being when all of the orifices 74 are exposed to the openings 72.

Diaphragms 64 and 66 provide very satisfactory seals for their respective manifolds, and they provide for free movement so that the slide may be positioned very easily with great accuracy. Also, when there is pressure within the manifold, the diaphragm is pressed against the slide so as to insure the proper sealing. The sizes and positioning of the orifices 74 are such as to provide a predetermined increase in the rate of flow of air into manifold 56 as the slide is moved toward its fully opened position. The slide bears indicia in the form of numbered lines to aid in providing the desired rate of flow. As will be further explained below, the rate of flow of the air determines the rate of flow of the gas to the burner unit and therefore controls the operation of the burner unit from the standpoint of the amount of heat pro-

duced. Each of the slides (see FIGS. 2 and 3) has a handle 33 with a main body portion 35 and an upturned flange 37 which is grasped by the fingers to move the slide between the fully-closed and fully-open positions. It has been found that this particular handle is ideal for quick and accurate adjustment of the slides. Also, when all of the slides are in the fully-closed position, the flanges 37 of the various handles are in alignment. Hence, if any of the slides is not in its fully-closed position, it will be quickly apparent to the observer.

As shown in the right-hand portion of FIG. 2, gases are supplied to the stove through a horizontal gas-supply manifold 80 extending along the front of the stove and connected to each of the gas cut-off valves 11. Each of the gas cut-off valves 11 has a non-magnetic body 82 with the valve closure being formed by a valve seat 84 and a steel ball 86 which is moved from and to the valve seat to open and close the valve. When the valve is in the open position as shown in full lines, gas flows from manifold 80 to the left through a passageway 88 and downwardly around ball 86 and past the valve seat through the valve opening to a gas supply chamber 100. The valve is opened and closed by the action of a cylindrical magnet 90 which is slidable vertically in the housing and guided by a pin 92 mounted at its upper end. Magnet 90 and ball 86 are urged downwardly by gravity and by a coil spring 94 mounted in the upper end of the magnet and they move upwardly only when the magnet is attracted by magnetic material above it. Accordingly, the slide 36 is of magnetic steel and it has a disk insert 96 of non-magnetic material which is moved into axial alignment with magnet 90 when the slide is in the fully-closed position. Hence, when a slide is positioned as shown in FIG. 2 or further to the right, magnet 90 is attracted to the slide and it lifts itself upwardly to the position of FIG. 2 and carries with it the steel ball 86 so as to open the valve. However, when any of the slides is moved to the fully-closed position, the non-magnetic disk 96 is in axial alignment with magnet 90 and the magnet is no longer drawn upwardly by attraction to the slide and it moves downwardly by the combined action of gravity and spring 94 and closes the valve.

With this arrangement, the first movement of any of the slides from its fully-closed position opens its gas cut-off valve 11 so as to permit gas to flow from the manifold 90 to the supply chamber 100. The gas flowing into supply chamber 100 passes through gas-flow regulator 13 and a chamber 104 to the venturi unit 15. Regulator 13 restricts the flow in a manner which is dependent upon the air pressure in manifold 56, namely, so as to maintain the gas pressure in chamber 104 at all times equal to the air pressure in manifold 56. Regulator 13 has a movable member 106 carried upon a stem from a diaphragm 108. Diaphragm 108 is urged upwardly by the gas pressure in chamber 104 with the aid of a coil spring 110, and it is urged downwardly by the pressure of the air in a chamber 112 above the diaphragm. Chamber 112 is connected to manifold 56 through a small opening 114, so that the air pressure in chamber 112 is the same as in manifold 56, except that the small size of opening 114 dampens the response to changes in the air pressure. Hence, when the air supply to manifold 56 is reduced, the reduced pressure in chamber 112 permits spring 110 to move member 106 upwardly so as to reduce the rate of gas flow. However, when the slide is moved outwardly so as to increase the rate of air flow, the pressure in manifold 56 is increased and there is the same increase in the pressure in chamber 112 which acts upon diaphragm 108 to increase the gas flow. In this way regulator 102 acts automatically at all times to maintain the gas pressure in chamber 104 equal to the air pressure in manifold 56.

From chamber 104 the gas flows through orifice 105 to an annular chamber 107 and thence through a plurality of radial holes 109 where it joins the stream of air

flowing to the burner unit. Orifice 105 has the characteristic that when the pressure in chamber 104 is equal to the pressure in manifold 56 gas is delivered to the air stream in the desired ratio. Hence, with the position of slide 36 controlling the rate at which air flows to the burner unit, the air pressure in manifold 56 acts through regulator 13 to produce an equal gas pressure in chamber 104, and there is a resultant gas flow through orifice 105 which gives the desired gas-air mixture to the burner unit. The respective mass flows of air as W_a and gas as W_g may be expressed as follows:

$$W_a = F1(P56 - P127)^{\frac{1}{4}}$$

$$W_g = F2(P104 - P107)^{\frac{1}{4}}$$

15 F1 and F2 are constants, and P represents the pressure in the correspondingly numbered zone. Regulator 13 insures that P104 equals P56. Holes 109 are relatively large in relation to the amount of gas flowing through them, so that P127 in the venturi throat equals P107. Therefore $(P56 - P127)^{\frac{1}{4}} = (P104 - P107)^{\frac{1}{4}}$ and so

$$\frac{W_a}{W_g} = \frac{F1}{F2}$$

20 In other words the mixture ratio of gas and air is a constant and depends on the values of F1 and F2. The actual value of F2 is dependent on the size of the orifice 105 so that by selecting various sizes of orifice 105 the mixture ratio of gas and air can be varied to suit the particular type of gas available. Also a restricting screw 122 may be adjusted so that its needle end 124 projects into the entrance to the orifice so as to adapt the orifice for the alternative gas supply. For this adjustment a screw plug 126 is provided which may be removed.

25 Referring to FIG. 4, burner unit 12 has a cylindrical plenum chamber 16 to which the proper gas-air mixture is supplied through its duct 18, and which has its top closed by a concave infrared burner element 20 of the wire-mesh type. Mounted in the side of hot gas chamber 22 is an ignitor unit 30 which is energized to ignite the burner unit. Extending between the top of plenum chamber 16 and the hot gas chamber 22, the top edge of which rests against the bottom surface of plate 6 and is sealed by a ceramic fiber gasket 24. A flue 26 extends from an opening in hot gas chamber 22 to an exhaust flue, and the elevated pressure permits the discharge of the products of combustion outside the building. Hence, the products of combustion are not discharged in the vicinity of the stove.

30 FIG. 5 is schematic and includes a representation of the electrical system. In alignment with each of the slides, there is a switch 110' which is held in its open position by the end of its slide whenever the slide is in the fully-closed position. These switches are in parallel, and the closing of any one of them connects the electrical supply to all of the ignitors 30 and also to the electric motor 112' of the blower. The first movement of any one of the slides from its fully-closed position opens its gas cut-off valve 11, and it also closes its electric switch 110' which energizes blower motor 112' and the ignitors 30. The ignitors are of known type which operate with very small current consumption, and it is satisfactory to energize all of the ignitors whenever any burner unit is being used. However, under some circumstances it is desirable to provide a separate switch for each of the ignitors and to energize each ignitor only when its burner is to be used.

35 It has been pointed out above that plate 6 is of heat-resistant glass which transmits infrared radiation. In producing the glass it is rendered somewhat translucent or opaque so that it prevents viewing the range components beneath the plate, except for a yellow glow when a burner unit is operating. It has been discovered that this glass has a color response to heat, which is very desirable in this particular use. Whenever one of the burner units is operating, it produces infrared radiation which passes through the disk portion of the plate 6 above that burner

unit, and that disk portion of the plate is heated by radiation and condition from the hot gases beneath it. As the temperature of the heated disk portion rises, it turns a greenish color, and that indicates to the user that particular burner unit is operating and that its plate portion is hot. Hence, the greenish-colored disk acts as a safety feature or warning, and guards against inadvertently touching the heated disk portion or placing combustible material upon it.

In the illustrative embodiment, the air-gas ratio is of the order of twelve to one at a fuel consumption rate of the order of 12,000 B.t.u. per minute. The elevation above ambient of the air pressure in manifold 46 is of the order of 1.8 to 2 inches of water. The air pressure in manifold 56 is not greater than that in manifold 46, and the gas pressure in chamber 104 is equal to the air pressure in manifold 56. The drop in pressure between chamber 104 and passageways 109 during maximum gas flow is of the order of 5 to 6 inches of water.

The present invention relates to the air-flow control valve 9 formed by the slides 32, 34, 36 and 38. While the illustrative embodiment of the invention is a household or commercial range, the valve is adaptable for other uses, and the scope of the invention is set forth in the claims.

What is claimed is:

1. In a control valve of the character described, a valve member having a side face, a sealing diaphragm of thin, flexible sheet material positioned along said side face and having an opening therethrough, said diaphragm having a sealing portion in close juxtaposition along its whole extent upon said side face to provide a fluid seal therewith and a laterally extending peripheral mounting portion fixed to said valve, and means providing a confining zone for retaining fluid under pressure exposed to said sealing portion and urging said sealing portion against said side face, and mounting means for said member to permit movement thereof parallel to the general plane of said side face.

2. In a control valve as described in claim 1 wherein said sealing diaphragm comprises a flexible sheet of Teflon.

3. The control valve as defined in claim 1 wherein said peripheral mounting portion is connected to said sealing portion by a generally laterally extending offsetting portion which supports said sealing portion in offset relationship to said mounting portion and presses said sealing portion against said side face of said valve member whereby said central portion is initially urged against said side face by said offsetting portion and is additionally urged in tight sealing relationship and in close juxtaposition therewith by said fluid under pressure to provide an extended sealing area against said valve member between said offsetting portion and the edge of said diaphragm opening.

4. The control valve as described in claim 3 wherein said valve member includes an elongated valve slide having a side face on opposite sides thereof and a second sealing diaphragm which is substantially identical with the first-mentioned diaphragm, wherein the sealing portions of each of said diaphragms rest respectively in intimate contact with its associated side face.

5. In a valve, the combination of a fixed valve structure having a fluid inlet portion and a fluid outlet portion, a valve slide, having a valve opening extending therethrough, mounted in said valve structure and adapted to move between an open valve position wherein said inlet portion is connected through said valve opening to said outlet portion and a closed valve position wherein said slide separates said inlet portion from said outlet portion, and a valve seal means of thin, flexible sheet material having a laterally extending peripheral mounting portion fixed to said valve structure and a flexible central sealing portion in close juxtaposition to the surface of said valve slide which is exposed to fluid under pressure in said inlet portion whereby said sealing portion is maintained in intimate contact along its whole extent against said valve slide under the action of said fluid under pressure and provides a sealing relationship therewith.

6. The valve as described in claim 5 wherein said laterally extending peripheral mounting portion comprises a peripheral flange fixed to said valve structure in spaced relation to said slide and an offsetting portion connecting said sealing portion and said flange, which supports said sealing portion in offset relationship to said flange and presses said sealing portion against said slide whereby said sealing portion is initially urged against said slide by said offsetting portion and is additionally urged in tight sealing relationship therewith by said fluid under pressure.

7. A valve structure as described in claim 5 which includes a second valve seal means substantially identical with the first-mentioned valve seal means, said valve seal means being mounted in back-to-back relationship upon the opposite sides of said valve slide and respectively providing seals for said inlet portion and said outlet portion.

8. A valve structure as described in claim 5 wherein said valve seal means has an opening therethrough, and wherein said opening in said slide is in alignment with said opening in said valve seal means when said valve is in the open-valve position.

9. A valve structure as described in claim 8 wherein said slide has a plurality of openings therethrough which are exposed progressively to said opening in said valve seal means thereby to provide a progressively increasing area of opening between said inlet portion and said outlet portion.
